UNITED STATES PATENT OFFICE

155,689

DESIGN FOR A COMBINED TEETHER AND RATTLE OR SIMILAR ARTICLE

Morton Davis, South Orange, N. J., assignor to
Joseph Davis Plastics Co., Arlington, N. J., a
corporation of New Jersey

Application November 22, 1948, Serial No. 149,747

Term of patent 14 years

(Cl. D83—1)

To all whom it may concern:

Be it known that I, Morton Davis, a citizen of the United States, residing in South Orange, in the county of Essex and State of New Jersey, have invented a new, original, and ornamental Design for a Combined Teether and Rattle or Similar Article, of which the following is a specification; reference being had to the accompanying drawing, forming a part thereof:

Fig. 1 is a top plan view of a combined teether and rattle or similar article embodying my new design; and

Fig. 2 is a perspective view thereof, taken on line 2—2 of Fig. 1.

I claim:

The ornamental design for a combined teether and rattle or similar article, as shown.

MORTON DAVIS.
